UNITED STATES PATENT OFFICE.

EMIL BAUR, OF ZURICH, SWITZERLAND.

PROCESS FOR THE RECOVERY OF HYDROGEN AND OXYGEN BY ELECTROLYSIS.

Application filed September 2, 1921. Serial No. 498,034.

To all whom it may concern:

Be it known that I, EMIL BAUR, residing at 53 Ottikerstrasse, Zurich 6, Switzerland, a citizen of Germany, have invented certain new and useful Improvements in Processes for the Recovery of Hydrogen and Oxygen by Electrolysis (for which I filed application in Germany May 29, 1920), of which the following is a specification.

10 The usual methods of producing hydrogen and oxygen electrolytically are deficient for two reasons. Because of the over-voltage, especially at the anode, there are polarizations of two volts and more even at

15 low current-densities, and because of the resistance of the usual aqueous electrolytes, of the polarization by dilution and of increasing overvoltage it is not possible to overcome moderate current-densities in the

20 range of size of one ampère per sq. dm. By lowering the polarization to about the value of the reversible voltage of the hydrogen-oxygen-cell and by increasing the current-density it would be possible to reduce the

25 expenses for the current and for the cell.

It has now been found that the electrolysis of molten caustic soda or potash or mixtures of the same, when they contain water, goes on without sensible overvoltage, 30 though the current-densities are taken very high. As a fact, it is known, that on electrolysis of water-containing caustic soda hydrogen and oxygen are generated (cf. Leblanc and Brode, Zeitschrift für Elektro- 35 chemie 1902, pag. 698), but in these experiences only little quantities of hydrogen and oxygen were evolved by an accessory reaction, hence it cannot be seen, that the gases are formed in a condition suitable for technical 40 purposes. With reference to aqueous solutions it was to presume, that an over-voltage would arise with higher current-densities. On the contrary it was found that no overvoltage appears even with very high current-densities. With a current-intensity of ten to twenty ampères per sq. dm and with a distance of four to five cm. between the electrodes the voltage of the cell

amounts to only 1,5 volts, so that both energy and space are much better availed than in all water-electrolyzers yet known.

The following process for the electrolysis of water is based on this knowledge:

The accompanying drawing illustrates one form of apparatus for carrying out the method.

In the said drawing,

Figure 1 is a vertical section.

Figure 2 is a vertical section at right angles thereto.

Like numerals indicate like parts in the different views.

A square vat 1 of iron-plate contains molten caustic soda or potash with a content of about five to ten per cent of water. The electrolyte is heated to about 250 up to 300° C. A set of small rectangular gasometers 2, made of iron-plate, plunge into the fused electrolyte. The gasometers contain insulated electrodes 4 of iron-plate 5, alternatively connected with the positive and negative pole. Out of every gasometer arises a pipe 3 to lead away hydrogen and oxygen. Special pipes provide the bath with a stream of water-vapour, which must be led to the cathodic chambers in the same rate, as the products of the electrolysis escape out of the cell. To produce the vapour, the heat, carried off by the gaseous products of the electrolysis can be used following to the well-known principles of heat-regenerating. The whole electrolytical cell may be surrounded by a heat-insulating cover and a suitable heating-wire, to keep the cell on the needed temperature.

I claim:

A process or method for the recovery of hydrogen and oxygen, which consists in electrolyzing with high current-densities molten caustic soda or potash or mixtures of the same, containing water in solution and restoring the water, decomposed by electrolysis, substantially as described.

In testimony whereof I have hereunto affixed my signature.

PROFESSOR EMIL BAUR.
